UNITED STATES PATENT OFFICE.

ROBERT HUGH CARSON, OF DANVILLE, ILLINOIS, ASSIGNOR, BY DIRECT AND MESNE ASSIGNMENTS, OF ONE-SIXTH TO GLEN W. REED, ONE-SIXTH TO MELVIN L. COUNTANT, ONE-SIXTH TO THOMAS J. HAWKINS, ONE-SIXTH TO HARVEY C. ADAMS, AND ONE-SIXTH TO GEORGE G. CARSON, ALL OF DANVILLE, ILLINOIS.

CENTRIFUGAL PUMP.

1,382,605.

Specification of Letters Patent. Patented June 21, 1921.

Application filed June 30, 1920. Serial No. 393,089.

To all whom it may concern:

Be it known that I, ROBERT H. CARSON, a citizen of the United States, residing at Danville, in the county of Vermilion and 5 State of Illinois, have invented a new and useful Centrifugal Pump, of which the following is a specification.

This invention has reference to centrifugal pumps and its object is to provide means 10 whereby fluid may be propelled with great force, but without the expenditure of undue power, to a destination.

While the invention is adapted to pumping various fluids it is particularly adapted 15 for pumping water or fluids of like character and, for simplicity of expression it will hereinafter be considered that the fluid to be pumped is water, without, however, necessarily confining the invention to the pumping 20 of such particular material.

In accordance with the invention the pump comprises a stator and a rotor housed within the stator in a manner to provide a water course from which water under pressure is discharged. The water is drawn 25 from a suitable source of supply and passes into the rotor from which it is driven by centrifugal force into a course between the outer periphery of the rotor and the inner 30 periphery of the stator, these parts being peculiarly formed and inter-related with the water passing from the rotor in trailing streams through trailing ports. The construction is such that the water bodily rotates with the rotor and flows from a central 35 intake to peripheral outlets and ultimately passes from the pump.

The rotor is of a capacity to contain a considerable amount of water, and in the 40 rotor is a single vane or partition extending from about the axis to substantially the inner peripheral wall of the rotor, wherefore a relatively large centrifugal force is stored in the rotor and this force being stored in 45 a highly mobile fluid readily flows into and then out of the rotor.

Provision is made for imparting to the water as it passes into the rotor a diversion and distributive tendency, whereby the 50 water is flowing up to about the speed of rotation of the rotor by the time it reaches the peripheral portion of the rotor.

Provision is also made for balancing the

stresses upon the rotor so that the water, after escape from the rotor and before escaping from the stator, so affects the rotor as to produce a floating pressure and thereby greatly reduces friction.

This application is a continuation in part of application No. 318,502, for centrifugal 60 pump, filed by me August 19, 1919.

The invention will be best understood from a consideration of the following detailed description taken in connection with the accompanying drawings, forming part 65 of this specification, with the understanding, however, that the invention is not confined to any strict conformity with the showing in the drawings, but may be changed and modified so long as such changes and modifications mark no material departure from the 70 salient features of the invention as expressed in the appended claims.

In the drawings:

Figure 1 is an elevation of a pump embodying the invention, together with a motor for driving the pump and a base common to both.

Fig. 2 is an axial section of the pump in a vertical plane.

Fig. 3 is a section on the line 3—3 of Fig. 2.

Fig. 4 is a section on the line 4—4 of Fig. 1.

Fig. 5 is an elevation of the rotor removed 85 from the pump.

Fig. 6 is an elevation of that half of the rotor shown on the right hand side of Fig. 5.

Fig. 7 is a section on the line 7—7 of Fig. 2.

Referring to the drawings there is shown a stator A, and a rotor B inclosed by the stator and rotatable therein. The stator comprises two members 1 and 2 in most part alike but differing in some minor details; 95 and the rotor comprises two similar members 3 and 4 having some minor details of difference.

Parts 1 and 2 of the stator A are similar castings with peripheries 5 in conical relation to the sides of the respective views of the stator, and each periphery 5 terminates in a radial flange 6 so situated as to be brought in face to face relation for a series of fastening bolts 7 by means of which the 105 two parts of the stator may be brought into

firm contact, suitable packing being used wherever advisable. The members of the stator or casing are furnished with legs 8 by means of which the stator may be firmly 5 secured to a base 9. The stator members 1 and 2 are provided with similar bosses 10 and 11 which, in the particular structure shown, are erected on the top portion of the stator, and the line of division between the 10 two bosses 10 and 11 may follow the line of division between the flanges 7.

Each boss 10 and 11 has a bore 12 opening through the top of the boss and communicating at the other end with the interior of 15 the respective stator member 1 or 2. The upper ends of the two bosses 10 and 11 are joined by a siamese coupling 13 secured to the bosses 10 and 11 by screws 14 or otherwise. The coupling 13 terminates in a 20 nipple 15 to receive a discharge pipe 16 by means of which water from the pump may be carried to any suitable point of disposal. Extending laterally through the coupling 13 is a rock shaft 17 carrying a vane 18 within 25 and traversing the course through the coupling 13 between the ends of the course where communicating with the bores 12. The shaft 17 extends through one side of the coupling and is there provided with a rock 30 arm 19 by means of which addition it may be rocked by hand or by connection with a moving part. The shaft 17 extends from a stuffing box 20 by means of which leakage at this particular point is prevented. The 35 vane 18 is designed to be rocked toward one or the other of the bores 12. This will cause back pressure to be exerted against one side or the other of the rotor B, thus tending to shift the rotor axially in accordance with 40 the direction of pressure. The arm 19 is connected by a link 21 to a lever 22 supported at the other end by a pivot 23 carried by a bracket 24 fast to one of the side members, say the member 2, of the stator on the side 45 of the axis of rotation remote from the vane.

At the axial portion of the member 2 of the stator there is formed a hub 25 through which there is produced a bore 26 for the passage of a shaft 27 constituting a drive shaft. The inner end of the bore 26 is counterbored as shown at 28 for the reception of a bearing sleeve 29 for the shaft 27. Connected to the shaft 27 by a coupling 30 or by other appropriate means is the shaft 31 50 of a prime mover 32 which may be conveniently in the form of an electric motor although not necessarily so. On the shaft 27 there is secured a sleeve 33 receiving a fork 34 on the lever 22, so that in the event of 55 longitudinal movements of the shaft 27 or of the lever 22 as controlled by the vane 18 each part will participate in the movements of the other.

The sleeve 28 terminates within the stator 60 in a head 35 provided with a facial annular

rib 36 and both members of the face plates 3 and 4 constituting the rotor are provided with disks 37.

The shaft 27 is continued through the plate 4 to the interior of the rotor and terminates 70 in a conical head 38 with the axis of the cone coinciding with the axis of rotation of the rotor B and shaft 27.

Each face plate 3 and 4 of the rotor terminates in a peripheral flange 39 flaring toward the central radial plane of the rotor and terminating in a thickened circumferential rib 40 by means of which the two members 3 and 4 of the rotor are secured together by screws 41, or in other appropriate manner. 80

The flare of flanges 39 corresponds to the flare of the peripheral portions 5 of the stator so that there is formed a chamber 42 within the pump between the stator and rotor of symmetrical portions in different parts. 85

Within the rotor there is provided a radial vane or blade 43 extending through the head 38 to the inner periphery of the rotor and secured to the rotor so as to maintain its relation thereto. Produced through the peripheral ribbed portion 40 of the rotor are a number of ports 44 of sufficient circumferential length, and also of sufficient width, to provide proper outlets for the rotor. The width or thickness of the rib 40 is less than that of the rotor, and the width of the ports 44 is less than that of the ribbed portion 40 through which the ports pass. These outlets or ports are slanted into trailing relation with respect to the direction of rotation. 90 This causes the streams of water, issuing from the ports, to assume a trailing relation to the rotor and consequently avoids those retarding influences which might occur from a sudden change of direction of the streams 95 of water. 100

Extending axially from the stator member 1 in alignment with the hub 25 is another hub or hollow boss 45 in which is seated a bearing sleeve 46 terminating at the inner end in a head 47 provided with a facial annular rib 48. 110

Fast to the rotor member 3 is a short tubular shaft 49 firmly secured to the member 3 and projecting therefrom toward the stator member 1 and into the sleeve 46, which constitutes a bearing for the shaft 49. 115

Secured in the outer end of the short hollow shaft 49 and projecting for a short distance toward the inner end of the shaft 120 is an impeller blade or blades 50 shaped to give a twisting impulse to water entering the hollow shaft 49 through a supply pipe 51 coming from a suitable source of water supply. (Not shown.) 125

The stator is provided with a central annular web 52 projecting into the chamber 42 into close relation to the central peripheral portion of the rib or vane portion 40 of the rotor, so that with the web 52 centrally lo- 130

cated with respect to the rotor, the water streams issuing from the ports 44 are each divided into two streams and ultimately pass to and through the respective passages or 5 channels 12.

When the pump is in operation with the pipe 51 connected to a supply of water and the motor 32 running, the incoming water flows through the pipe 51 and is acted upon 10 by the twisting impeller 50 causing the flow of water, with a rotary impulse already imparted to it, into the rotor where it meets the conical head 38 and is given a direction change toward the periphery of the interior 15 of the rotor, the impeller having already imparted to the body of water a rotating movement corresponding to that of the rotor. There is advantage in the preliminary moving impulse imparted to the body of water 20 within the rotor in correspondingly conserving power which would otherwise be absorbed in setting up the bodily rotary movements within the rotor at the peripheral portion of the latter where the leverage is 25 less efficient than at the hub portion of the rotor.

The single straight radial vane 43 acts as an abutment for the water within the rotor so that such water is in the form of a solid 30 body of water with a progressive movement due to the escape of the water through the ports of the rotor and the replenishing of the water through the intake pipe 51 with the course of flow of the water within the 35 rotor free from sharp turns with attendant friction and resistance. The single vane or abutment 43 tends to maintain the water within the rotor in solid compact form without threshing or foaming and consequent 40 loss of compactness.

The ports 44 are symmetrically disposed about the rotor and are of such cross sectional size that their combined effective area is about equal to that of the inlet of the 45 rotor. Ordinarily the combined cross sectional area of the trailing ports will be equal to or somewhat less than the area of the inlet, but under some circumstances the combined area of the ports 44 may be slightly 50 greater than the cross sectional area of the pipe 51.

The result of engaging the streams of water in the plane of rotation by the annular web 52 so set as to just clear the middle 55 of the rib or vane 40 on the rotor is to set up a constant tendency to centralize the rotor. If for any reason the stream on one side of the rotor should become greater than that on the other side thereof, the additional 60 resistance offered to the outflow of the stream through the outlet port 12 on the same side of the pump will impart an axial thrust to the rotor to force it back to the equalizing position.

65 While the equalizing washer or annular

web 52 may be omitted without serious loss of efficiency, whether or not the equalizing web or blade 52 be used, will depend upon the working conditions under which the pump is installed. 70

While the vane 18, which is in the nature of a baffle plate and located within the siamese head 13, is shown and described as automatically operated by connection with the power shaft 27, the automatic feature 75 may be omitted and the vane or baffle plate may be set and secured in place when the pump is installed, or it may be manually changed from time to time as conditions demand. The baffle plate or vane is supplemental to the other equalizing features of 80 the invention.

What is claimed is:

1. A centrifugal pump comprising a stator and a rotor inclosed thereby, the pump 85 having an annular fluid course between the stator and rotor and the rotor being provided with an axial inlet, a peripheral series of outlet ports and a single interior abutment vane or blade reaching from the axis of 90 the rotor to the periphery thereof.

2. A centrifugal pump comprising a stator and a rotor inclosed thereby and the stator and rotor defining an annular fluid course between them, the rotor having an 95 axial inlet and a peripheral series of trailing outlet ports and a single interior radial abutment vane or blade reaching from the axis of the rotor to the periphery thereof.

3. A centrifugal pump provided with a 100 rotor, an axial inlet, peripheral outlets, and a single vane or blade within the rotor and extending radially to the peripheral portion thereof.

4. A centrifugal pump, comprising a 105 stator, a rotor within and in substantially concentric relation to the stator, a hollow shaft communicating axially with the rotor to deliver fluid thereinto, impeller blades in the hollow shaft at one side of both the 110 stator and rotor, and means in the rotor for diverting fluid driven by the impeller blades into a radial path toward the periphery of the rotor within the latter, said rotor having peripherally located outlet ports in its mid- 115 radial plane.

5. A centrifugal pump provided with a 120 rotor having a peripheral series of outlet ports of less width than the interior thickness of the rotor, a tubular shaft delivering axially into the rotor, and means constructed to force fluid through the tubular shaft into the rotor and there change its course into a radially outward direction, said rotor having peripherally located outlet ports. 125

6. In a centrifugal pump, a hollow rotor provided with a substantially radial interior vane or blade extending from the axis of the rotor to the peripheral portion thereof with the said rotor having an axial inlet and a 130

peripheral exterior fin or rib with outlet ports extending through the vane or rib.

7. In a centrifugal pump, a hollow rotor provided with a substantially radial interior vane or blade extending from the axis of the rotor to the peripheral portion thereof with the said rotor having an axial inlet and a peripheral exterior fin or rib with outlet ports extending through the vane or rib, 10 said ports trailing toward their outlet ends with respect to the direction of rotation of the rotor.

8. In a centrifugal pump, a stator, a rotor within the stator in concentric spaced relation thereto to define an annular fluid course between the stator and rotor, said rotor having inner peripheral walls approaching the central radial plane of the rotor and terminating in a thickened circumferential rib 20 with trailing outlet ports therethrough, and the stator having an annular dividing web midway of its width and in close relation to the outlet ports whereby to divide the streams issuing from the outlet ports of the 25 rotor toward the opposite sides of the course between the stator and rotor.

9. In a centrifugal pump, a stator, a rotor within the stator in concentric relation thereto and the stator and rotor defining an 30 annular fluid course between them, said rotor having peripheral outlet ports in centralized relation to the rotor and the stator having an annular dividing web midway of the width of the stator and in close relation 35 to the outlet ports of the rotor, whereby to divide the streams issuing from the rotor ports toward opposite sides of the course between the stator and rotor, the inner peripheral wall of the rotor and the outer peripheral wall of the stator tapering toward 40 the central radial plane of each, and the rotor being formed with an intermediate exterior radial rib or fin through which the ports extend.

45 10. A centrifugal pump comprising a stator and a rotor mounted within which, said stator and rotor defining an annular fluid course between them, the rotor having a peripheral annular radial flange with out-

let ports extending therethrough, and the 50 stator having outlet ducts on opposite sides of the rotor with their entering ends closer to the axis of the rotor than their outlet ends, means for directing said streams issuing from the rotor ports to opposite sides of 55 the rotor and through the outlet ducts of the stator, a siamese connection into which the outer ends of the ducts of the stator discharge, and a controlling vane operable from the exterior of the stator and located 60 in the siamese connection for constricting one or the other of the outlets from the stator.

11. A centrifugal pump comprising a 65 stator and a rotor mounted within it, said stator and rotor defining an annular fluid course between them, the rotor having a peripheral annular radial fin with outlet ports extending therethrough, and the stator having outlet ducts on opposite sides of the 70 rotor with their entering ends closer to the axis of the rotor than their outlet ends, means for directing the streams issuing from the rotor ports to opposite sides of the rotor and through the outlet ducts of the 75 stator, a siamese connection into which the outer ends of the ducts of the stator discharge, and a controlling vane operable from the exterior of the stator and located 80 in the siamese connection for constricting one or the other of the outlets from the stator, said pump also being provided with a shaft for driving the rotor and connections between the shaft and the vane in the siamese connection, whereby the rotor is 85 axially responsive to variations in pressure on opposite sides of the rotor to cause a movement of the vane in opposition thereto so that the variations in pressure on the rotor tending to move the latter axially are 90 counter-acted and the rotor is caused to maintain a sensibly constant position in the stator, and has a floating support in the fluid passing through the pump.

In testimony, that I claim the foregoing 95 as my own, I have hereto affixed my signature.

ROBERT HUGH CARSON.
